Primary Examiner — Cynthia Underwood(74) *Attorney, Agent, or Firm* — Rader, Fishman & Grauer PLLC(57) **CLAIM**

The ornamental design for a camera, as shown and described.

DESCRIPTION

FIG. 1 is a perspective view of a first embodiment of a camera showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

Portions in broken lines are for illustrative purpose only and form no part of the claimed design. Dot-dash broken lines define the boundaries of, but not included in, the claimed design.
